UNITED STATES PATENT OFFICE.

WILLIAM H. HOPKINS AND WALTER R. WILSON, OF OAKLAND, CALIFORNIA.

FLOOR-MAT.

1,072,729.

Specification of Letters Patent. Patented Sept. 9, 1913.

Application filed November 19, 1912. Serial No. 732,390.

To all whom it may concern:

Be it known that we, WILLIAM H. HOPKINS and WALTER R. WILSON, citizens of the United States, residing at Oakland, in the county of Alameda and State of California, have invented new and useful Improvements in Floor-Mats, of which the following is a specification.

An object of the invention is to provide a mat of simple and durable construction and which can be folded for shipment.

The invention embodies, among other features, a mat preferably made of metal and including spring-like S-shaped members arranged to coact to frictionally retain the mat in an open position, the said mat being foldable so that the same can be readily shipped in a compact bundle.

In the further disclosure of the invention reference is to be had to the accompanying drawings, constituting a part of this specification, in which similar characters of reference denote corresponding parts in all the views, and in which:

Figure 1 is a plan view of the mat, showing the same in open position; Fig. 2 is a side elevation of the mat in open position; Fig. 3 is a side elevation of the mat in closed position; Fig. 4 is a vertical transverse sectional view taken on the line 4—4 in Fig. 1; and Fig. 5 is a perspective view of one of the S-shaped members.

Referring more particularly to the views, we disclose a mat 10 comprising a series of U-shaped frames 11, each preferably made of a single piece of wire-like material and having the ends thereof bent to form hooks 12, with the hooks of the first frame adapted for pivotal connection with the second frame and so on until a sufficient number of frames are employed to secure a mat of the desired length, after which a securing rod 13, preferably formed of a single piece of wire-like material and bent at the ends to form hooks 14, is adapted for connection with the last frame, with the hooks 14 of the locking rod engaging the hooks 12 of the last frame, as shown.

A series of S-shaped members 15 are employed to form the body of the mat and are preferably arranged in rows, with the first row of members having the medial portion of the first U-shaped frame 11 passing through the outer curved ends thereof to secure the members in adjacent position on the frame, with the medial portion of the second frame

11 passing through the inner curved ends of the said S-shaped members, the second row of S-shaped members 15, however, having the medial portion of the second U-shaped frame 60 also passing through the outer ends thereof, with the outer curved portions of the second row of S-shaped members interposed between the inner curved portions of the first row of S-shaped members, as shown, it being thus 65 seen that the spring-like tension formed by the curved ends of the S-shaped members will result in a frictional spring-like contact between the inner ends of the first row of S-shaped members and the outer ends of 70 the second row of S-shaped members. In a similar manner, a third row of S-shaped members have connection with the third U-shaped frame and the inner ends of the second row of S-shaped members are connected 75 to the said third U-shaped frame and interposed between the outer ends of the S-shaped members in the third row in the same manner that the first and second rows of S-shaped members have connection with the 80 second U-shaped frame 11, it being further seen that the adjacent U-shaped frames 11 are connected in the manner mentioned heretofore. Now when the last U-shaped frame 11 has been secured in position with the medial portion of the last U-shaped frame passing through the outer ends of the last 85 row of S-shaped members and the inner ends of the second last row of S-shaped members, the securing rod 13 is secured to 90 the last U-shaped frame in the manner mentioned heretofore and passes through the inner ends of the last row of S-shaped members, thus forming the completed mat. A series of reinforcing links 16 are provided, 95 a pair of links being employed for each row of S-shaped members 15 with one link of each pair connected to the medial portions of the first and second U-shaped frames to one side of each row of S-shaped members 100 and the other link connected to the medial portions of adjacent U-shaped frames at the other end of adjacent rows of S-shaped members, the pair of links, however, having connection with the medial portion of the last U-shaped frame and the securing rod 13, the said reinforcing links being arranged 105 on the medial portions of the U-shaped frames adjacent the points of connection of one U-shaped frame with the next U-shaped 110 frame, thus permitting of readily folding the mat 10 by folding the second row of S-

shaped members to the first row, the third row upon the second row and the fourth row upon the third row, as shown in Fig. 3.

As mentioned heretofore, the curved ends 5 of the S-shaped members, when the S-shaped members are supported on the U-shaped frames 11, are normally pressed together and when the mat is arranged in an open position the curved end of one S-shaped member in one row will abut against the curved end of another S-shaped member in an adjacent row, thus causing one S-shaped member to frictionally engage another and exert an outward pressure which 15 will result in a pressure being exerted against the reinforcing links 16 to frictionally cause the S-shaped members to remain in open position and also frictionally lock the reinforcing links in open position.

It will therefore be seen from the foregoing description and the drawing that the mat consists of few parts of simple and durable construction and in which a series of rows of S-shaped members are movably carried by a series of adjacent U-shaped frames with the ends of each frame connected to the next frame in order to provide a structure whereby one row of S-shaped members can be conveniently folded and superimposed 25 upon the next adjacent row of S-shaped members, with suitable reinforcing links interposed between each row of S-shaped members and the lateral ends of the U-shaped frames supporting the same. It 30 will, therefore, be readily understood that a particular function is accomplished in employing the S-shaped members described 35

herein, in that the curved end of one S-shaped member abutting against the curved end of an adjacent S-shaped 40 member will result in a lateral pressure carried from one S-shaped member to the other at the curved ends thereof, the said pressure being produced by the curved ends of the S-shaped members in that the 45 curvature of each of the said ends is restricted when the ends are carried on the U-shaped frames.

Having thus described our invention, we 50 claim:

In a mat, the combination with a series of U-shaped frames, with one frame connected to the next adjacent frame, of S-shaped members carried by the said frames and arranged in adjacent rows, the said S-shaped 55 members in each row being movable on the said frames to superimpose one row of S-shaped members upon another when the said frames are relatively folded, with the ends of the S-shaped members in one row frictionally engaging ends of the S-shaped members in an adjacent row to exert a lateral pressure on the said U-shaped frames at their points of connection and frictionally retain the said U-shaped frames in open 60 position.

In testimony whereof we affix our signatures in presence of two witnesses.

WILLIAM H. HOPKINS.
WALTER R. WILSON.
